(57) **CLAIM**

The ornamental design for an integrated catheter, as shown and described.

DESCRIPTION

FIG. 1 is a perspective view of an integrated catheter showing my design;

FIG. 2 is a bottom perspective view of the catheter of FIG. 1;

FIG. 3 is a front elevational view of the catheter of FIG. 1; FIG. 4 is a rear elevational view of the catheter of FIG. 1; FIG. 5 is a top plan view of the catheter of FIG. 1; FIG. 6 is a right-side elevational view of the catheter of FIG. 1;

FIG. 7 is a left-side elevational view of the catheter of FIG. 1; and,

FIG. 8 is a bottom plan view of the catheter of FIG. 1. The broken lines shown in FIGS. 1-8 are for illustrative purposes only and form no part of the claimed design.
